(57) **CLAIM**

The ornamental design for a boot attachment for a boot dryer, as shown and described.

DESCRIPTION

FIG. 1 is a perspective view of a boot attachment for a boot dryer showing our new design;

FIG. 2 is a right side elevation view thereof;

FIG. 3 is a front elevation view thereof;

FIG. 4 is a rear elevation view thereof;

FIG. 5 is a top plan view thereof; and,

FIG. 6 is a bottom plan view.

The broken line showing of the base in FIGS. 1-6 is included for the purpose of illustrating portions of the boot attachment for a boot dryer and forms no part of the claimed design.
